DESIGN FOR AN AIRPLANE

William K. Ebel, Kingsville, Md., assignor to The
Glenn L. Martin Company, Baltimore, Md.

Application April 17, 1940, Serial No. 91,731

Term of patent 14 years

To all whom it may concern:

Be it known that I, William K. Ebel, a citizen of the United States and resident of the city of Kingsville, in the county of Baltimore and State of Maryland, have invented a new, original, and ornamental Design for an Airplane, of which the following is a specification, reference being had to the accompanying drawings, forming part thereof.

Figure 1 is a perspective view of an airplane embodying my new design;

Figure 2 is a side elevational view thereof;

Figure 3 is a top plan view thereof; and

Figure 4 is a front elevational view thereof.

I claim:

The ornamental design for an airplane, substantially as shown.

WILLIAM K. EBEL.
